(57) **CLAIM**

The ornamental design for a marble spinning flow nozzle as shown and described.

DESCRIPTION

FIG. 1 is a top plan view of a marble spinning flow nozzle; FIG. 2 is a front elevational view thereof. The rear, left side and right side elevational views being a mirror image thereof;

FIG. 3 is a bottom view thereof;

FIG. 4 is an isometric view thereof; and,

FIG. 5 is an isometric view thereof, showing our design in use.

The broken lines represent environmental structure and form no part of the claimed design.
